United States Patent Office

Des. 180,909

Patented Sept. 3, 1957

180,909

TURNER OR SIMILAR ARTICLE

Richard S. Latham, Chicago, Ill., assignor to Ekco Products Company, Chicago, Ill., a corporation of Illinois

Application March 15, 1956, Serial No. 40,625

Term of patent 14 years

(Cl. D44—29)

Fig. 1 is a front elevational view of a turner or similar article, showing my new design.

Fig. 2 is a side elevational view thereof.

The essential features of the design reside in the portions shown in full lines.

I claim:

The ornamental design for a turner or similar article, as shown and described.
